UNITED STATES PATENT OFFICE.

WILLIAM J. EDWARDS, OF CHICAGO, ILLINOIS, ASSIGNOR TO FREDERICK C. AUSTIN, OF SAME PLACE.

GRADING AND DITCHING MACHINE.

SPECIFICATION forming part of Letters Patent No. 393,467, dated November 27, 1883.

Application filed March 20, 1882. Serial No. 267,900. (No model.)

To all whom it may concern:

Be it known that I, WILLIAM J. EDWARDS, a citizen of the United States, residing at Chicago, in the county of Cook and State of Illinois, 5 have invented certain new and useful Improvements in Grading and Ditching Machines, of which the following is a specification.

This invention is particularly designed as an improvement upon the construction of 10 grading and ditching machine characterized by Letters Patent No. 275,614 of the United States, issued to me on the 10th day of April, 1883, it being understood, however, that various features of improvement herein involved 15 may, where applicable to other grading and ditching machines, be so employed.

The object of my invention generally stated, is to increase the general efficiency and serviceability of a grading and ditching machine, 20 or "grader and ditching-machine," as I prefer to term it.

Certain special objects herein involved and more particularly specified are to permit 25 greater freedom of certain desirable movements on the part of the plow; to facilitate the proper positioning of the plow relatively to the elevator and with reference to the character of the soil; to apply the draft in plowing in an improved way, in order, first, that 30 while the plow may freely line itself the plow-beam shall be kept from crowding against either the frame of the machine or the front wheel at the plow side thereof; secondly, that a caster-wheel, preferably carried at the forward end of the plow-beam, shall be maintained in proper running position with relation to any and all inclinations of the ground 35 over which it travels; thirdly, that the caster-wheel shall be prevented from running into the front supporting-wheel at the plow side of the machine; fourthly, that the plow may more readily dodge obstructions and line itself; fifthly, that when the plow is tilted for cutting sod the draft shall relieve the landside of the 40 plow, and, finally, that the draft shall come upon the middle of the front axle, and hence any strain incurred by the main frame of the machine will be in a way best adapted to the 45 capability of the main frame for resisting 50 strain.

Certain further objects are to facilitate and insure the deposit of stalks and trash onto the endless conveyer-belt; to improve the construction of the elevator; to provide along the elevator an improved construction of guideway; to prevent dirt from getting onto the lower leaf of the endless conveyer-belt; to facilitate both the prolongation and shortening up of the elevator; to facilitate the shortening up or the lengthening of the conveyer-belt 55 proportionally to the desired length of the elevator; to provide certain improvements in the power-transmitting devices for operating the elevator-belt; to improve the running gear of the machine and permit the application of such 60 quantity of lubricating matter to the axles and their bearings as may insure easy running of the machine for a considerable length of time, and to provide certain novel and improved 65 details tending to increase the strength, durability, and general efficiency of a grader and 70 ditching-machine.

To the attainment of the foregoing and other useful ends my invention consists in matters 75 hereinafter set forth, and particularly specified in the claims.

In the accompanying drawings, Figure 1 represents in side elevation the main portion of a grader and dumper embodying my invention, the side illustrated being the one at which 80 the plow is arranged for operation, and hence termed either the "receiving" or "plow" side of the machine in contradistinction to the opposite delivery side from which the plowed-up earth is to be delivered from an elevator. 85 Fig. 2 is a detail representing a section taken through the caster-wheel standard on the line 2 2, Fig. 1, and illustrating in plan the caster-wheel scraper and its support, with the outer end portions of the arms upon which the cas- 90 ter-wheel is journaled broken away. Fig. 3 is a detail representing a vertical section through the caster-wheel scraper and its support on the line 3 3, Fig. 2. Fig. 4 represents in side elevation the delivery side of the main portion of 95 the grader and dumper, the parts thereof above the platform being removed for convenience of illustration. The near rear supporting-wheel is also removed in this view. Fig. 5 represents in side elevation a portion of the plow- 100

beam with a bracket attached thereto and adapted for establishing jointed or flexible connection between the plow-beam and a swing-controlling-bar, G, which latter is shown in cross-section. Fig. 6 represents a vertical section taken transversely through the plow-beam on the line 6 6, Fig. 5, and illustrates a portion of the edge of bar G, which, when said bar is in place, as in Fig. 4, will be its rear edge relatively to the front and rear ends of the ditcher and grader. Fig. 7 represents in perspective the end portion of the bar G that is included in Fig. 6, the slotted plate 52, shown secured to the rear edge of the bar in said Fig. 6, being, however, omitted in Fig. 7, in order to more clearly illustrate a kerf or recess formed in the end of the bar. Fig. 8 represents a vertical section taken transversely through the machine on the line 8 8, Fig. 1, and looking toward the rear of the machine. Fig. 9 is a detail representing an adjustable hinged connection between the plow-beam and its rear controlling-bar, E, which said connection is adapted to take the place of the adjustable hinged connection shown in Fig. 8. In said Fig. 9 the plow-beam is shown in cross-section, as in Fig. 1, and a portion of the controlling-bar represented. Fig. 10 shows a portion of the elevator-belt understood to be passing around the belt-driving drum or roller at the delivery end of the elevator, and represents means for connecting the meeting ends of two adjacent belt-sections. Figs. 10^a and 10^b are details illustrating the belt-fastening. Fig. 11 represents a vertical section taken transversely through the machine on the line 11 11, Fig. 1, and looking toward the front end of the machine. Fig. 12 is a detail representing on a somewhat larger scale the slotted end 40 of the bar 33 shown in Fig. 11. Fig. 13 represents in perspective a socket-piece adapted as a support for one end of the rear-beam-controlling bar E, and designed to have a sliding pivotal connection with the slotted end 45 portion of the fixed bar 33. Fig. 14 may be regarded as a sectional plan taken on a substantially horizontal plane just below the level of the main platform-frame or just below the main longitudinal sills of the body-frame, 50 the design being to represent in top plan the principal portions of the machine below the sills or platform. In this view the delivery-end portion of the elevator is, for convenience of illustration, broken away, as is also the forward end portion of the plow-beam. Fig. 15 principally represents, partly in top plan and partly in horizontal section, the clutch and clutch-actuating device, whereby power can be applied for operating a sprocket herein employed for driving a link-belt, which in turn is to operate a belt-roller at the delivery end of the elevator. This view indicates in full lines the shifting-clutch member closed or in clutch and in dotted lines said member open 55 or out of clutch. Fig. 16 is a face view of the clutch member 152, which is toothed to provide the sprocket. Fig. 17 is a like view of

the shifting-clutch member. Fig. 18 represents in perspective one of a pair of boxes herein employed as journal-supports for a belt-roller at the receiving end of the elevator, said box being shown in top plan, Fig. 14. Fig. 19 represents a longitudinal section taken centrally through said box. Fig. 20 represents, on a somewhat larger scale, a section taken through the rear wheels and boxes for the rear axle on a vertical plane coincident with the axis of the axle, which latter is, however, for clearness of illustration, not shown in section. This view also represents the pawl-and-ratchet devices on the rear axle. Fig. 21 is an end or face view of the hub 139, shown keyed upon the rotary axle in Fig. 20, and represents the internal set of ratchet-teeth. Fig. 22 is a like view of the cap 143, provided with pawls for engaging the ratchet-teeth of the aforesaid hub, and shown in Fig. 20 secured to the hub of one of the supporting-wheels. Fig. 23 represents a top plan view of the lower half of one of the boxes for the axle of Fig. 20, said lower half being exposed by removing the upper half, which in the next succeeding figure is shown applied. Fig. 24 represents a section taken through one of said axle-boxes on the line 24 24, Fig. 23, the upper and lower halves or parts of the box being fitted together. Fig. 25 represents in perspective two sections of the elevator coupled together and secured in alignment, said sections being the one at the delivery end and the next preceding section. Fig. 26 represents a pair of the guide-guards or side-boards, F', shown in other views arranged over and parallel with the length of the elevator-belt, this particular view serving to more clearly represent a lock-joint between two abutting ends of such sides or guards and one of their supporting attachments or arms, 82. Fig. 27 represents the abutting ends of the two guards or side-boards of the preceding figure and shows the locking device on a somewhat larger scale. Fig. 28 represents in perspective the two elevator-sections of Fig. 25 in position to separate their opposing ends, the object of this view being to illustrate a construction of 115 break-joint whereby the elevator-sections can be detached from one another or connected together and brought into alignment, as may be required. Fig. 29 represents one of the connecting-hooks 111 of the preceding figure. Fig. 30 is a top plan view of several of the elevator-sections secured in alignment and illustrates a belt-driving roller arranged at the delivery end of the elevator. This view also includes a portion of the link-belt and shows in horizontal section a shield, M, herein employed for covering the sprocket upon one of the driving-roller's journals. Fig. 31 is a longitudinal central section through Fig. 30 on line 31 31. Fig. 32 represents the abutting 120 end portions of a couple of the longitudinal side bars of elevator-sections of the preceding figure and illustrates a form of coupling which, when found desirable, can be employed in 125 130

place of the hooks of Fig. 28. Fig. 33 represents in perspective the coupling-plate of the preceding figure. Fig. 34 represents, on a larger scale, a section taken longitudinally 5 through the belt-driving roller on line 34 34, Fig. 30. Fig. 35 is a section taken transversely through the elevator on line 35 35, Fig. 30. Fig. 36 represents a section taken on a vertical plane through the forward support-
10 ing-wheels, the boxes for their axle, and front bolster, the plane of this section being coincident with the axis of the axle, which, however, is shown in elevation. Fig. 37 represents an end view of the axle and front bolster of the preceding figure with the wheel removed, and shows a portion of the half-circle or fifth-wheel and certain adjuncts, including a portion of the middle longitudinal sill, 3, of the platform or main frame of the machine. Fig. 38 is a
15 detail representing in rear elevation certain bearings for the king-bolt of the preceding figure. Fig. 39 represents a vertical section taken through the front axle on the line 39 39, Fig. 36, and shows in side elevation, on a some-
20 what larger scale, the king-bolt and its bear-
ings.
25

The construction of the main frame herein represented is in many respects similar to that illustrated in my former patent, and while it
30 is understood that no limitation is placed upon such construction it is desirable to briefly refer to the arrangement shown in order to more conveniently locate by description certain attachments, some of which, as will be herein-
35 after seen, in addition to other functions, tend to improve the general construction of the frame, which is desirably made as light as may be compatible with necessary strength. The principal portion of the structure herein
40 illustrated comprises a horizontal rectangular body or platform frame, A, adapted at certain points for operatives to stand upon, and supported upon front and rear bolsters, which are in turn supported from the front and rear
45 wheeled axles.

The body or platform frame may include the two longitudinally-arranged side sills, 1 and 2, and a middle longitudinal sill, 3, secured at their ends to the front and rear bol-
50 sters and at points intermediate of the two bolsters connected together by two or more lower cross-sills, 4 and 5, and a corresponding pair of upper cross-sills, 6 and 7.

B indicates the plow-beam suspended along-
55 side the machine and carrying a plow, C, suitable for the work required in a machine of this character.

The plow-standard 8 is, for the sake of combined strength and lightness, made of chan-
60 nel-iron and pivotally attached to the beam by a pivot-bolt, 9, having its bearings in plates secured to opposite sides of the beam. By thus pivotally hanging the plow from the beam the plow can be swung about its piv-
65 otal support in order to determine the angle of penetration. As a means for securing the plow in such adjustment, it is provided with

a rearwardly-arranged and upwardly-extend-
ing arm or bar, 10, attached at its lower end to the plow and at its upper end adjustably
70 connected with a segment-plate, 11, Figs. 1 and 4, which is secured to the beam and pro-
vided with a series of bolt-holes for such pin or bolt as may be employed for connecting the
75 arm 10 with the segment-plate. The arm 10, while serving to permit the plow to be set at a desired angle, also serves as a brace which will effectively resist all ordinary strain to
80 which the plow may be subjected by the re-
sistance opposed to progress. Should, how-
ever, the plow meet with a sudden and im-
passable resistance or barrier during the ad-
vancement of the machine, the pin or bolt by
85 which arm 10 is attached to the segment-plate
will be cut off by the arm and the plow per-
mitted to yield until the machine can be
stopped, in place of a general breakage of
either the plow or its connection with the beam
through the pivoted standard 8. The plow
and its standard are, therefore, to be made of
90 considerable strength, and to such end the
channel-iron standard subserves a useful pur-
pose. As a further simple means for bracing
the plow, the mold-board is connected with
the channel-iron plow-standard by a short
95 bent brace-rod, 12, Fig. 14, bolted both to
the mold-board and to the plow-standard.

The plow can be placed under the control
of an operator standing upon a platform on
the body-frame A, substantially as in my
former patent, to which end the forward end
100 of the plow-beam can be quickly raised or low-
ered to give to it the required running depth
by means of a rope or chain, 13, Fig. 1, at-
tached to the forward end portion of the plow-
beam and carried up over a pulley, 14, to a
short rotary drum or shaft, 15, which is mount-
ed in a bearing, 16, Fig. 8, above the main
body-frame and provided with a hand-wheel,
17, whereby the operator can raise and lower
110 the forward end of the plow-beam at will.
The somewhat elongated bearing 16 is herein
shown as a support for the end portion of shaft
115 15 next adjacent to the hand-wheel, and as a
means for further steadyng the opposite end
of the shaft said end is mounted in a short
bearing, 18, at the upper end of an inclined
brace-rod, 19, which inclines downwardly to-
ward the forward end of the machine, and is
at its lower end secured to the side sill, 1,
120 whereby it is arranged in position to best with-
stand the pull of chain 13 on the shaft 15.
The rear end of the plow-beam can also be
raised and lowered at will by an attendant
standing upon the machine, the chain 20 for
125 this purpose being at one end connected with
the rear portion of the plow-beam and at its
remaining end attached to a rotary drum or
shaft, 21, which is arranged longitudinally
with relation to the length of the machine and
130 mounted in bearings on the prongs or forks of
a double-armed bearing-piece, 22.
The shaft 21 is provided with a suitable hand-
wheel, 23, and the double-armed bearing-piece

22 is secured upon a standard, 24, rising from the main body-frame and suitably secured to a convenient portion thereof—such, for example, as the side sill, 1. The bearing 16 for the 5 rotary winding-shaft 15 is formed upon one of the bearings for the winding-shaft 21, in which way the standard 24 also sustains a bearing for the winding-shaft 15, that is arranged transversely to the length of the machine, while by 10 the presence of rod 19 the provision of an additional standard is rendered unnecessary. Locking devices are employed for locking the aforesaid hand-wheels as soon as the ends of the plow-beam have been raised or lowered to 15 the required extent, and these locking devices can be arranged as in my former patent or in any other desirable way.

The standard or bracket 25, arranged at one of the forward corners of the main body frame 20 as a support for maintaining pulley 14 at the desired elevation, is simply provided at its base with two arms or legs, one of which is secured to the side sill, 1, and the other secured to the front bolster of the running-gear.

25 The plow-beam carries at a point in advance of the plow a rolling colter, herein shown connected with the plow-beam by an attachment which I have made the subject of an application for Letters Patent of even date herewith, 30 although, if desired, other constructions of rolling-colter attachments could, as a matter of course, be employed. The plow-beam is capable of a limited end play or movement, the extent of its forward movement being governed by a chain, 26, Fig. 1, attached to the beam at a point preferably in advance of the colter. This chain can be simply caught at 35 some desired point along the upper portion of its length upon a hook, 27, secured to the side sill, 1, at a point somewhat to the rear of the point of attachment of the chain to the beam, so as to extend back in opposition to the draft upon the plow-beam. In this way the extent to which the plow-beam may be drawn forward 40 can be determined by the length of chain between the plow-beam and the point at which the chain is attached to the main body-frame of the machine.

The rear end of the plow-beam is flexibly or 50 pivotally connected with a bar, E, which is arranged transversely, or substantially so, to the plow-beam and capable of several distinctive movements—namely, a horizontal swing or vibratory motion in a horizontal or substantially horizontal plane, a vertical swing or vibratory motion in a vertical or substantially vertical plane, and an end movement or longitudinal reciprocatory action. As a means for permitting such movements on the part of 55 bar E, it is at one end connected with the plow-beam by a hinge or pivotal joint and at its other end pivotally attached by a vertical pivot bolt or pin, 28, Fig. 14, to a bearing, 29, which is supported so as to be capable of both 60 a sliding movement in a direction transversely with relation to the plow-beam and a rotary 65 play about a horizontal axis. This bearing 29

preferably consists of a socket-piece adapted to receive the bar E and provided with bolt-holes in its top and bottom sides for the pin or bolt 28, one of said bolt-holes, 30, being shown in Fig. 13. Said socket-piece is also provided with a laterally-projecting stud or pivot, 31, engaging in a guide-slot, 32, which can be formed in any suitable bearing piece or fixture, but which is herein shown formed in the lower portion of an inclined brace-bar, 33, that is at its lower end secured to any suitable fixture—such, for example, as a frame-bar, 34, attached to and depending from the side sill, 2—and at its upper end secured to the middle longitudinal sill, 3, of the body-frame, as shown, for example, in Fig. 11. The pendant support 34 is arranged in rear of the elevator—that is to say, between the elevator 85 and the rear axle—whereby the bar E will be arranged at a point where it may have the desired extent of horizontal swing without interfering with the elevator.

The bar E is capable of a limited extent of 90 lateral vibratory play in the socket-piece 29, it being seen that a slight vibratory play of the bar in such socket piece or bearing will permit a much greater extent of swing on the part of its end that is connected with the 95 plow-beam, and that such swing is intended to be and in practice is ample for all practical purposes. The bar E is also provided with a line of vertical bolt-holes, as indicated at 35, Fig. 14, whereby an end adjustment of this 100 freely-swinging and longitudinally-reciprocatory bar can be readily effected by a transfer of the pin 28 from one to another of such bolt-holes.

The end adjustment of bar E is to be made 105 with reference to the position of the plow relatively to the lower receiving end of the elevator F, having an endless apron or belt upon which the soil is received from the plow and carried up and over to one side of the machine, it being understood that for different soils it is desirable that the plow shall work more or less closely to the receiving end of the elevator, the working position of the plow in this respect being determined by the character 110 of the soil delivered from the plow to the elevator. The end or longitudinal play of the bar E allows the plow to line itself to different soils and to dodge to one side or the other to avoid obstructions or adapt itself to the 115 character of the ground, which is frequently such as to render it difficult for the plow as a whole to pursue an exact rectilineal course. This play on the part of the plow is permitted by reason of the sliding pivotal connection between the bar E and a guideway, such as set forth, which said connection also permits the 120 rise and fall of the rear end of the plow-beam. The horizontal vibratory swing of bar E permits an end movement on the part of the plow-beam, whereby the plow can be made to work 125 farther forward or more to the rear relatively to the receiving end of the elevator, it being also desirable to position the plow in this re- 130

spect with reference to its delivery of different soils to the elevator. The limit of the forward end movement of the plow-beam can be determined by the chain 26, while the limit 5 of its end movement in a rearward direction can be determined by an adjustment in length of the draft-chain hereinafter described.

The hinge or pivotal connection between the vibratory and reciprocating bar E and the plow-beam involves an adjustable bearing, whereby the plow can be tilted to one side with reference to the cut to be made—as, for example, in cutting sod it is desirable to tilt the plow to one side, so as to make a clean cut instead of a tearing cut. In several of the figures this adjustable hinge-connection between bar E and the plow-beam is similar to a connection shown in my said patent between the rear end of the plow-beam and a transversely-arranged 10 bar having a sliding pivotal connection with a supporting bracket or hanger, such connection (see, for example, Fig. 8) consisting of a hinge-pintle plate or leaf, 36, provided with one or more curved slots for bolts, by which it 15 is adjustably attached to bar E and connected with the plow-beam B by a pintle or pivot-bolt, 37, having its bearings in a bracket, 38, secured to the plow-beam and at its ends extending through eyes or pintle-sockets on the 20 plate 36. A simplified adjustable hinge-connection between the bar E and plow-beam is, however, shown in Fig. 9, wherein the connection comprises a stout metal strap or flat bar, 39, secured to the lower edge of bar E and 25 projecting to some extent from the end of the bar, and an inclined rod or bar, 40, having at its lower end a slot, 41, for a bolt, 42, by which it can be adjustably secured to the bar E. These bars 39 and 40 are at their ends next to 30 the plow-beam provided with eyes for a pivot-bolt, 43, which can be attached to the beam or any suitable bracket thereon—such, for example, as to the bracket 38, hereinbefore described. In this way, by adjusting the rod or 35 bar 40 in its connection with bar E, the plow can be tilted to one side to the required extent.

The forwardly-arranged swinging bar G, which, like the bar E, is employed to control 40 the movements of the plow, is arranged transversely with relation to the plow-beam and attached thereto by a flexible or hinged connection. The bar G is capable of both a vertical and a horizontal swing or vibratory motion, 45 and is further susceptible of an end or longitudinal adjustment. As a means for permitting such movements on the part of the bar G, it is at one end flexibly connected with the beam and at its opposite end pivotally attached 50 to a support, 44, (see, for example, Fig. 4,) by a vertical pivot pin or bolt, 45. This pivot permits a horizontal swing on the part of the bar G in correspondence with a similar swing 55 on the part of the rearward controlling-bar, E, so as to allow an end movement of the plow-beam, for purposes hereinbefore mentioned. This pivotal connection between one end of

the bar G and the support 44, or other suitable bearing for such end of the bar, permits the latter to swing in a vertical or substantially vertical plane in unison with such rise and fall of either the forward end of the plow-beam or of the entire plow-beam, as the case may be, it being understood that in either instance the greatest extent of rise and fall that 70 may be incurred by the end of bar G that is flexibly attached to the plow-beam will necessitate so slight a motion on the part of the pivotally-supported end of the swinging bar that the vertical pivot 45, simply inserted through 75 a hole of proper diameter in the swinging bar, will, for all practical purposes, permit such end tilt or vertical swing on the part of said bar.

The bars E and G, being pivotally supported 80 independently of one another, may therefore, so far as the rise and fall of the plow and plow-beam is concerned, either tilt or swing in unison or otherwise, accordingly as the beam may either rise and fall equally at both ends or tilt, 85 as the case may be. The bar G is also adjustable endwise, for which purpose it is provided with a series of bolt-holes, 46, Fig. 14, for the removable pivot 45, in which way the bar can be adjusted longitudinally by selecting one or another of such holes for the pivot. When the plow is tipped to one side for cutting sod by adjusting the hinged connection between bar E and the plow-beam, as hereinbefore set forth, the bar G and also the bar E can be adjusted 90 in order to shift the plow-beam laterally and to an extent to prevent the plow from running into or working in too close proximity to the receiving end of the elevator. On the other hand, these two bars can be adjusted endwise, 95 so as to shift the plow-beam laterally, and thereby vary the distance between the plow and the receiving end of the elevator whether the plow be tilted to one side or not. Thus, for plowing up and delivering loose soil to the elevator, 100 the plow should work closer to the elevator than in plowing and delivering clay or other soil having more body and permitting the plow to make a wider furrow.

In my said former patent the draft upon the 115 plow is attained by a draft-chain connected at its forward end with the main body-frame at one of the front corners thereof and at its rear end attached to the plow-beam at a point adjacent to the plow, the line of such draft-chain 120 being oblique or diagonal relatively to the length of the plow-beam, for purposes therein set forth. In the machine herein involved the draft is from the pole or middle point of the front axle, and is attained by extending the 125 draft-chain H back from such point and attaching it to the forward controlling-bar, G. In this way, in place of drawing obliquely from one corner of the machine in a direction tending to "diamond" the main body-frame, 130 the draft is in a direction coincident with the length of the machine and midway of its longitudinal sides, whereby all pull upon the machine tends to "square" its frame, since such

pull is in a direction with the longitudinal sills of the frame and transverse to its cross-sills. This change from a side draft to a center draft not only adds materially to the life or period 5 of usefulness of the machine and avoids frequent repairs, but also permits the same to be made with less bracing.

The draft-chain is made adjustable in length in any suitable way—for example, by an adjustable link or connection, 47, interposed 10 along its length, as in Fig. 14, whereby the limit of the rearward swing of the bar G can be varied in order to cause the plow to work more or less forward or back relatively to the 15 receiving end of the elevator. In this connection provision is made for shifting the pivotal end of bar G to the front or rear, so as to permit the bodily lateral adjustment of the bar either forward or back. By thus limiting the 20 extent of swing to the rear on the part of bar G, by positioning the pivotally-supported end of said bar and properly adjusting the length of the draw-chain, the plow can be permitted to work farther forward or back relatively to 25 the receiving end of the elevator and with reference to the character of the soil, it being desirable to work the plow farther back relatively to the receiving end of the elevator for loose soil than for clay or like earth. This 30 adjustment of the pivotally-supported end of the bar G can be readily attained by providing for its removable pin or pivot-bolt 45 a series of bolt-holes in the support 44, a line of such holes, 48, being shown on the upper portion 35 of such support in Fig. 14.

In order that the draft upon the plow may be in a line coincident with the plow-beam and from a point in front of the mold-board, the hinge or flexible connection between the plow-beam and the bar G is made at a point to one side of the plow-beam and in front of the mold-board of the plow. In this way, the draft 40 through the draft-chain H being on the bar G, and the connection between such bar and the plow-beam being in front of the mold-board, the draft will act as a landside or greatly relieve the landside of the plow. This arrangement also serves to keep the plow-beam from crowding against or running into either the 45 side of the machine or such one of the front wheels as the plow-beam may be extended alongside of, and further serves to maintain a easter-wheel, I, at the forward end of the plow-beam at all times in proper position relatively 50 to the surface of the ground over which it is traveling. Said feature is also particularly serviceable in positioning the easter-wheel to run up banks or furrows or run along inclined banks at a time in the process of road-making 55 when such banks incline downwardly toward the lowest level traversed by the main supporting front wheel that is opposite the easter-wheel, and also prevents the easter-wheel from getting under or running under such main front supporting-wheel.

As an efficient connection between the bar G and the plow-beam, the latter is provided

with a bracket which inclines outwardly from the plow-beam and is provided at a point properly remote from the plow-beam with a 70 horizontal pivot, 49. (Best shown in Figs. 5 and 6.) The bar G is at its end nearest the plow-beam provided with a horizontally-cut kerf or recess, 50, Fig. 7, for the reception of said horizontal pivot, which extends through 75 said recess in a direction transversely to the bar G and parallel with the plow-beam.

To the front edge of bar G is secured a plate, 51, which, if preferred, may extend the entire length of the bar to strengthen the same, and 80 in said plate is formed a pivot-hole arranged opposite the recess 50 in the bar and adapted for the reception of the pivot 49 at a point adjacent to what may be termed the "forward" 85 end of the pivot relatively to the machine in which it is employed.

To the rear edge of bar G is secured a plate, 52, Fig. 6, which is extended alongside the recess in the bar and opposite such recess provided with a longitudinal slot, 53, for the passage of the rear end portion of the pivot. The hanger is provided with two pivot-bearings, respectively opposite the front and rear edges of the bar, and adapted for supporting the front and rear ends of the pivot, a simple construction of bracket-support for the pivot being an inclined arm or bar, 54, secured at its upper end to the plow-beam and at its lower end provided with a bearing, 55, for one end of the pivot, and a somewhat similarly secured 100 and arranged inclined arm, 56, provided at its lower end with a bearing, 57, for the forward end of the pivot, and having at a point above such bearing a diverging brace-arm, 58, that is secured to the plow-beam. It is, however, 105 herein understood that other forms or constructions of hangers or brackets could be employed for a like purpose.

The foregoing construction of connection between the bar G and the plow-beam adapts it to the movements of the bar and plow-beam, it being seen that during an end movement of the plow-beam and a horizontal swing on the part of bar G the arc traversed by the end of such bar next adjacent to the plow-beam will 110 cause the rear end portion of the pivot to be drawn toward one or the other of the ends of slot 53, according to the direction in which the plow-beam and bar G are moved, and also that such connection affords a joint which 115 permits the beam to be inclined to one side in 120 tilting the plow.

From the foregoing it will be seen that the devices herein illustrated for supporting the independently-arranged front and rear plow-beam-controlling bars E and G operate substantially as universal joints, both adjustable in position upon fixtures or supports on the main frame of the machine, the joint for the rear bar, E, being also a sliding joint to permit lateral play or automatic side movement 125 on the part of the rear end of the plow-beam; also, that by means of such joints a ready end adjustment can be given both of said two con-

trolling-bars, and also that the joint for the forward bar, G, can be shifted in a direction coincident with the line of progression.

The working position of the plow during the advancement of the machine can therefore by such adjustments be determined with relation to the character of the soil and the delivery of the same to the elevator. At the same time the plow is so suspended and controlled that while being properly guided and kept to its work it will have a perfect freedom and ease of movement, permitting it to line itself and otherwise adapt itself to the work to be performed without unduly straining any of its guiding or controlling adjuncts.

With reference to the action of bar G, the support or bearing for its vertical pivot at the end farthest from the plow-beam can obviously be of any suitable construction; but as a special construction of support herein also utilized as a brace the support 44 consists of a proximately rectangular loop or oblong socket formed at the lower end of an upwardly-inclined and forwardly-extending brace-rod, 59, (see particularly Fig. 4,) which is at its upper end secured to the side sill, 2, of the body-frame, the lower loop portion, 44, of such rod being secured to and serving to brace one of the standards of a frame for supporting certain sprockets for the elevator raising and lowering chains, hereinafter more particularly referred to. In this connection it may be observed that the lower substantially rectangular eye or loop, 44, at the lower end of the brace-rod 59 serves as a most efficient bearing for the pivot-bolt 45, since both its upper and lower horizontal portions can be provided with bolt-holes, so as to afford bearings for the pivot-bolt both above and below the bar G. This loop or pivot bearing 44 is also preferably braced by a rod, 60, arranged diagonally to the length of the main body-frame, and at its ends attached, respectively, to the cross-sill 4 and the loop 44, as indicated in Figs. 1 and 4, in which way, while the lower portion of the upright 101 is in one direction braced by the rod 59, it is in effect braced in a direction oblique to the rod 59.

As an extremely simple means for holding the plow down to its work in hard or baked soil, the plow-beam is at its rear end provided with a standard, 61, Figs. 1 and 8, which rises from the plow-beam to within convenient reach of the foot of an attendant standing upon a rear platform, 62. The standard is at its upper end provided with a suitable foot rest, 63, the whole constituting a foot-piece or presser-bar, whereon the attendant may without delay throw sufficient of his weight to keep the plow down to its work.

At the forward end of the plow-beam a hollow standard, 64, for the caster-wheel is clamped against the end of the beam by clamps 65, the beam being preferably concaved, so as to form a seat for such standard. Upon the lower end of this hollow standard 64 is swiveled a hub, 66, as in Fig. 3, a convenient arrangement being to provide a two-part hub having an in-

ternally-arranged annular groove, 67, wherein the heads of a cross-bolt, 68, extending through the standard, can be received preparatory to bolting the two parts of the hub together. This hub is provided with a laterally-arranged proximately V-shaped bearing for a scraper, 70, which is adjustably bolted upon such bearing and extended rearwardly therefrom into position for freeing the caster-wheel from such dirt as, in road and ditch making, will otherwise adhere to the caster-wheel to an extent to seriously interfere with its free running.

Referring particularly to Fig. 3, it will be observed that the support or bearing 69, while adapted to extend somewhat over the caster-wheel to provide a firm and reliable support for the scraper, has its under side curved in a direction forwardly away from the periphery of the caster-wheel, so that from the point where the lower side of the support or bearing 69 is nearest the rim of the wheel the space between the two from such point forward widens rapidly. The result of this arrangement is that should any loose earth be left on the wheel by the scraper and carried forward by the rotation of the wheel it will run off in place of collecting between the wheel and the under side of the scraper support or bracket 69.

The caster-wheel is journaled in boxes provided at the lower ends of a pair of arms, 71, which are bolted to the hub 66 and from such hub inclined downwardly to the rear. The boxes are desirably adapted to contain a suitable quantity of lubricant and constructed so as to effectively exclude dirt. The caster-wheel, in conjunction with the scraper, constitutes a serviceable and important feature in a practically successful grader and ditcher, and is particularly applicable to the class of work to be performed.

The elevator F is arranged transversely with relation to the length of the machine and extended under the main body-frame, so as to bring its receiving end in position to receive the earth from the plow, which delivers the soil onto the endless traveling elevator-apron or conveyer-belt 72, thereby permitting the belt to convey the same upwardly to the discharge end of the elevator and there discharge the same either onto the road or into a wagon, as the case may be.

The elevator comprises in its general construction one or more (but preferably a plurality of) frames or sections arranged to constitute a desirably long-jointed roll-supporting frame, which carries a suitable power-driven roll for operating the endless belt, and idler-rolls for supporting and permitting the free running of the same.

The elevator is provided with a longitudinally-arranged guideway extending over and along the belt from the receiving end to the discharge end of the elevator, and having its sides arranged to keep the dirt and other matters delivered from the plow to the belt from running off the side edges of the belt, thereby permitting the belt which constitutes the bot-

tom of such guideway to conduct the dirt and other matters from the point of reception to the proper point of discharge. In addition to the desirability of causing the plow to work 5 in such position relatively to the receiving end of the elevator and character of soil to be delivered as will cause a proper delivery of the plowed-up soil onto the belt, it is highly desirable and important that all trash 10 plowed up—trash such as stalks, wild sun-flowers, and the like—shall be properly guided and delivered into the aforesaid guideway of the elevator, thereby not only preventing the same from being left behind, but, what 15 is of great importance, preventing such matters from getting caught either about the journals or journal-boxes for the belt-roll at the receiving end of the elevator or about any other parts of the machine at such locality, it 20 being found that the first arrestment of any stalks or trash at such points induces such rapid subsequent accumulation of like matters as to require a stoppage of the machine and a loss of much time in removing the obstructions. To avoid such objectionable features 25 in a grader and ditching-machine, one of the guides or sides F' of the guideway along the elevator is at the receiving end of the elevator extended from such point by a curved 30 guard, K, which, in effect, forms a prolongation of the guide arranged first to diverge from the opposite corresponding guide F' in a direction toward the plow and to then sheer off reversely in a direction forwardly and away 35 from the plow, as best illustrated in Fig. 14. This arrangement of guard K relatively to the receiving end of the elevator and the plow serves to effectively cause trash—such as stalks and the like—to be guided to and thrown upon 40 the elevator-belt between the guides F', which extend longitudinally along such belt, and, moreover, serves to prevent such trash from being thrown over either the journals of the belt-roll at the receiving end of the elevator 45 or the boxes 73, that are provided for said journals. Should the guides F' be made of metal, the end of one of such guides could be bent to form the guard K. The guides F' are, however, for the sake of both economy and 50 lightness, formed of wooden boards, and in such case the guard K is formed by a bent metal plate secured at one end to the guide and at its opposite end secured to the upturned end of a bar or plate, 74, arranged transversely to the length of the elevator and secured to the lower edges of the elevator-frame 55 at points substantially below the belt-roll 75, Fig. 8, at the receiving end of the elevator. The guard K thus arranged also drops somewhat from its rear end, that is secured to the guide to its forward end, that is secured to plate 74, as illustrated in Fig. 1, in which way, while the face of the curved guard opposite the plow may be vertical, or nearly so, the 60 guard as a whole lowers or inclines toward its forward end. The bar or plate 74 serves both to brace the elevator at the receiving end and

to support the guard K, which latter serves in turn to support the forward end of the guide F', to which it is attached, and brace such 70 guide against earth thrown against it from the plow.

The guard K is stationed at one side of the plow, but set forward and away from the plow to an extent to permit free passage of the soil 75 from the plow to the elevator, but will be found of extreme utility as a means for causing stalks and the like to be properly deposited upon the elevator. Should, however, any stalks or the like pass between the plow and 80 elevator without being directed by the conjoint action of the guard and plow onto the belt in the first instance, the guide F', which is to the rear relatively to the advancement of the machine, will force such stalks or trash onto the 85 belt by reason of the prolongation of its forward end beyond the point where the elevator-belt passes around the front belt-roll, 75, as at 76. This extended end 76 of one of the guides or side-boards of the elevator-guideway 90 is supported and steadied by a curved bar, 77, which is secured both to the guide and to the plate 74, that is attached to the under side of the elevator-frame.

The elevator-frame, while practically a long 95 frame extending continuously substantially from the receiving to the delivery end of the elevator, is desirably divided into a plurality of sections, the first division back of the receiving end of the elevator being principally 100 made to afford a joint adapted to allow the portion of the elevator which extends out laterally from the machine to effect a side delivery from the latter to be readily raised and lowered, while the next succeeding divisions 105 occurring along such laterally-extended portion of the elevator are to permit it to be shortened up or lengthened by the removal of a section. These several frame-sections of the elevator preferably involve a substantially similar 110 construction, thereby preserving a substantial uniformity of structure throughout the entire length of sectional frame. The construction herein shown consists of a pair of oppositely-arranged upper side bars, 78, as best 115 shown in Figs. 25, 28, and 35, and a pair of lower oppositely-arranged side bars, 79. The upper and lower bars are separated by suitable 120 blocks arranged at intervals along the frame and the whole braced and connected together 125 by appropriate cross-bars, some of which are desirably arranged transverse to the length of the frame and others diagonally to such length.

The upper longitudinally-arranged side bars are provided with appropriate bearings for a 130 series of idler-rolls, 80, employed for supporting the upper leaf of the elevator-belt, the bearings for such roll-journals being at points to set these upper idler-rolls somewhat higher than the top edges of the said upper side bars, 135 78, in which way the belt can be made of sufficient width to extend over the upper longitudinal edges of the side bars 78, as illustrated in Fig. 35. The spaces occurring alongside

the frame by reason of the elevation of its side bars 78 relatively to its side bars 79 are covered by shields or plates 81, secured along their longitudinal edges to the upper edges of the upper side bars, 78, and along their lower longitudinal edges secured to the lower side bars, 79. The boards forming the guides F' are arranged over the elevator-belt and raised therefrom to an extent to prevent frictional contact between the belt and guides, which latter are held and braced in position by curved supporting-bars 82, secured at their upper turned-down ends to the outer sides of the guide-boards and at their lower ends secured to the lower side bars, 79, of the frame.

The shields or plates 81, which may be said to form sides or side coverings for the elevator-frame, slope outwardly from the edge portions of the belt, which, as illustrated in Fig. 35, is of sufficient width to discharge any dirt that may work its way under the guides F' onto the sloping side plates or side coverings, 81, of the main frame. In this way the plates or frame-sides 81 will shed any dirt that may find its way to the outer edges of the belt, and by reason of the arrangement of the upper leaf of the belt relatively to the frame-sides 81 such dirt as may fall off the edges of the upper leaf of the belt will be prevented from getting onto the lower leaf of the belt, it being understood that the falling of dirt within the elevator-frame would soon tend to clog up its operative parts and render necessary a stoppage of the machine and the laborious task of cleaning out such accumulation of dirt.

By setting the upper side frame-bars at a less distance apart than that at which the lower side frame-bars, 79, are relatively arranged, the slope of the plates or frame-sides 81 is readily attained, and at the same time provision made whereby the belt can have its side edges extended somewhat beyond the ends of the upper belt-rolls, 80, and brought into position to discharge any waste dirt onto the sloping frame-sides 81.

The guides F' are preferably arranged somewhat back from the edges of the belt—that is to say, somewhat toward the longitudinal middle line of the belt—which arrangement is conveniently attained by the supports 82. By this disposition of the guides better results can be attained than where the edge of the belt travels directly opposite the vertical face of a side wall or side-board, particularly since in the latter instance an objectionable quantity of the dirt that is being carried along by the belt will sift between the guide and edge of the belt.

The portion of the elevator-frame which extends under the main body or platform frame A of the machine can be made in one length or frame-section, while the remaining portion of the frame, that is arranged to extend from the delivery side of the machine, can be composed of one or more lengths or frame-sections, as may be desired. To permit a free and desired extent of rise and fall on the part of

such portion of the elevator as projects from the delivery side of the machine, and also to allow the same to be swung out of the way when the services of the plow and elevator are not required, the frame-section of the elevator next succeeding the frame-section that is suspended under the main or platform frame A can be and herein is suspended from the main body-frame of the machine separately from the first or lower frame-section of the elevator that is suspended from the main body or platform frame, in place of being directly hinged to said lower frame-section.

The devices herein shown for suspending and adjusting the frame-section of the elevator that is arranged under the main body or platform frame A and the devices for raising and lowering the portion of the elevator that is arranged as a prolongation of said section are substantially the same as in my former patent—that is to say, the frame-section of the elevator which is arranged below the platform-frame A, and which constitutes the receiving end portion of the elevator, is at the receiving end suspended by raising and lowering chains 83 from a rotary winding drum or shaft, 84. This winding-shaft 84 is mounted upon an elevated frame, L, that rises from the main body or platform frame of the machine, and is provided with a hand-wheel, 85, by which it can be operated by an attendant standing upon the rear platform, 62. In this connection suitable means—such as a pawl-and-ratchet device (shown at 86)—can be used for temporarily locking the winding-shaft 84 against rotation. The higher end portion of the aforesaid frame-section of the elevator, which is toward the delivery side of the machine, is suspended from the cross-sills 4 and 5 of the body or platform frame by swinging arms or straps 87, Figs. 8 and 11, which straps are provided with several pivot-holes for the pivot-bolts by which they are pivotally attached to the sills, in which way an adjustment of such connections between the body-frame and this end portion of the elevator can be made when desired. The said elevator-frame section is also further placed under control of an attendant by the inclined connecting-rods 88, pivotally attached at their lower ends to the said elevator-frame section at points toward its higher end, that is nearest the delivery side of the machine, and at their upper ends connected with cranks or arms 89 (one of which is shown in Fig. 8) upon a horizontal rock-shaft, 90. The rock-shaft 90 is arranged longitudinally with relation to the length of the machine and supported in bearings in or upon the cross-sills 4 and 5 and the rear bolster, as indicated in dotted lines, Fig. 1, and is extended back to the rear of the machine, whereat a hand-lever, 91, is provided for operating such rock-shaft and a swinging toothed bar, 92, arranged for locking the hand-lever after it has been operated to adjust the elevator-section.

The vertically swinging or tilting portion

of the elevator, which is suspended from the main body-frame of the machine, and which is in the nature of an extension of the portion of the elevator that lies under the main body-frame, can be raised and lowered by the raising and lowering ropes or chains 93. These ropes or chains 93 are attached to the elevator toward or near its delivery end and pass over pulleys or sprockets 94, mounted upon the elevated frame L. This elevated frame also provides bearings for a rotary winding drum or shaft, 95, to which the chains 93 are attached, so that by operating a hand-wheel, 96, upon the winding-shaft the elevator can be raised or lowered from its delivery end. In this connection any suitable locking device can be employed for locking the winding-shaft against rotation, so as to conveniently hold the elevator-extension at the required angle.

As a means for hinging to the main body-frame of the machine the section or portion of the elevator which constitutes an extension of the section or portion that is arranged under the main body or platform frame, the frame-section of the elevator that is to be thus hinged is provided at or adjacent to the corners of its end that is nearest the body of the machine with hinge or bracket plates 97 and 98, Figs. 11 and 14, which are respectively attached by pivotal connections to the lower ends of brace rods or bars 99 and 100. Each one of these hinge or bracket plates 97 and 98 is bolted to the elevator frame-section, and is provided with a series of bolt-holes for the pivot by which it is attached to its allotted supporting-bar. In this way the end of the elevator frame-section next adjacent to the elevated end of the elevator frame-section that is under the main body-frame of the machine can be adjusted in height, it being understood that the matching end of the elevator frame-section that is under the main body-frame of the machine can, by means hereinbefore described, be adjusted in height in correspondence with the adjustment of the adjacent end of the next succeeding section, and hence the two opposing ends of such sections be maintained in proper relationship to afford a suitable joint at this point along the elevator.

The inclined bars 99 and 100 are arranged transversely to the length of the machine and secured to the frame-work of its body portion. These said bars are at their upper ends conveniently secured to the middle longitudinal sill, 3, of the main body-frame of the machine, and adjacent to their lower ends are desirably secured to the lower portions of standards 101 and 102, which are bolted to the longitudinal side sill, 2, of the body-frame, so as to rise therefrom and form portions of the elevated frame L. By thus securing the inclined brace-bars 99 and 100 to the middle of the body-frame and to the lower ends of standards 101 and 102, which drop below the main uprights of the elevated frame L, said standards are braced by bars which afford pivotal bearings for the hinged extension portion of the

elevator-frame. In this connection it will also be observed that the brace-rod 59, having at one end a support, 44, for one end of the swinging plow-beam guiding or controlling bar G, connects the lower end of the upright 101 with the side sill, 2, and is arranged in a plane at right angles to the plane in which the brace 99 is arranged, the brace 59 corresponding in this respect to an inclined brace, 103, which serves to connect the lower end of the upright 102 with the side sill, 2, as in Fig. 4.

In order to adapt the guides F' to the joint occurring at the junction between the receiving-end portion of the elevator, that is arranged below the main body-frame of the machine, and the extension or delivery-end portion of the elevator, that is controlled by the raising and lowering chains 93, the strips or boards 104, that are supported from the elevator frame-section of the receiving-end portion of the elevator and arranged to form the sides of a guide or passage way over and along the same, can be arranged to have their higher ends simply lap the adjacent ends of the guide-boards or guideway-sides 105, that are supported over the next succeeding elevator-section, as in Fig. 14.

The delivery-end or extension portion of the elevator, which is pivotally suspended from the braces or bearings attached to the uprights 101 and 102, can be composed of one or more lengths or sections, it being more desirable, however, to form it of a plurality of sections, whereby for wide roads or other service requiring a long elevator the several sections can be united to form an elevator of the desired length, whereas when the required service demands a short elevator one or more of the sections can be taken out.

The boards or guideway-sides allotted to said sectional extension portion of the elevator can be made in sections corresponding to the number of elevator-sections included in such extension portion and temporarily connected together, as illustrated in Figs. 26 and 27, wherein a couple of sections of such boards or guideway-sides, 105 and 106, are arranged end to end and connected together by a plate, 107, which is at one end secured to one board—for example, the board 105—and at its other end provided with a slot, 108, to receive a bolt which is secured to the section 106 and provided with a nut that can tighten up against the slotted plate. This arrangement permits the sides of the guideway allotted to any one section of the extension portion of the elevator to be removed with such section when the same is taken out to shorten the elevator, and on the other hand permits the sides of the guideway along such extension portion of the elevator to be made continuous and rigid when the sections of such extension portion are connected together.

In Fig. 31 the extension portion of the elevator is shown as comprising three frame-sections connected together at the joints by angle-plates 110, Figs. 32 and 33, which provide seats or half-sockets for and are temporarily

bolted to the meeting end portions of the lower side bars, 79, of the elevator frame-sections. In Figs. 25 and 28 another way of temporarily connecting together those elevator frame-sections is illustrated. In each of said figures two elevator frame-sections are shown connected together by break-joints formed by hook-shaped bars 111, secured to the side bars of one frame-section at an end thereof and 10 adapted for engagement with links or loops 112, that are secured to the next adjacent frame-section. In this way the joints can be broken, as in Fig. 28, and the sections entirely disconnected either for shipment or for taking 15 out any one of the elevator frame-sections, so as to shorten up the elevator, while on the other hand, when desired, the sections can be readily connected by bringing the hooks into engagement with the loops, as in Fig. 28, and 20 then bringing one section into alignment with the other section, as in Fig. 25, wherein the ends of the side bars of one frame-section are understood to abut squarely against the opposing ends of the side bars of the adjoining section. 25

The frame-section of the elevator employed as the extreme end section at the delivery end of the elevator is provided with bearings for the belt-driving roll 113, which is preferably 30 somewhat larger than the idler belt-rolls. The boxes 114 for the journals of this belt-driving roll are adjustably held upon the elevator frame-section, which at this end may have its lower side bars, 79, prolonged somewhat beyond 35 the terminals of its upper side bars, 78, so as to provide suitable seats or bearings for the journal-boxes. While the journal-boxes 114 can be adjusted in various ways, in order to either tighten or line up the elevator-belt, 40 a simple and preferred way is to provide the boxes with base-plates having slots for the reception of bolts, by which they can be held down upon their seats or bearings, and to employ short adjusting hook-bars or hook-bolts 45 115, Fig. 30, having bearings in brackets or angle-plates 116 on the ends of bars 79 of the end elevator frame-section and arranged to place their hook ends in engagement with suitable eyes or holes in the base-plates of the 50 boxes, in which way by adjusting the nuts 117 on threaded portions of such adjusting-bolts the required adjustment of the journal-boxes can be effected.

The boxes 114 are each adapted to contain 55 a suitable quantity of lubricating matter to insure the free running of the belt-driving roll, and in this connection it will be observed that the boxes 73 (see also Figs. 18 and 19) for the journals of the belt-roll 75 at the receiving end of the elevator are likewise adapted to contain a suitable quantity of lubricating matter, and are herein rendered adjustable by adjusting hook-bolts 118, Fig. 14, applied in a manner similar to that in which the hook-bolts 115 are applied for adjusting the journal-boxes at the delivery end of the elevator.

It is understood that should it be desired to

shorten the elevator by removing a section of the middle section of the extension portion of the elevator can be removed, (where, for example, such extension portion comprises three sections,) after which removal the extreme outer section carrying the large belt-driving roll can be coupled to the section that is hinged to supports at the side of the main body-frame of the machine. 75

To prevent dirt from falling from the upper leaf of the belt down between the ends of the upper frame-section side bars, 79, and the driving-belt roll 113, shields 119, Figs. 30 and 80 34, which preferably consist of pieces of some suitable flexible material, are attached to the bars 79 and arranged to cover portions of the ends of the belt-driving roll, thereby preventing dirt from the load that is being carried 85 along the elevator from falling upon the lower leaf or fold of the belt.

The chain or link-belt sprocket 120, that is secured upon the axle or one of the journals of the belt-driving roll 113, is covered by a 90 casing or shield, M, which is removably attached to the frame-work of the elevator at this point. This shield is particularly serviceable as a means for preventing operators from getting caught by the sprocket at the delivery end of the elevator, it being found that in delivering to wagons the drivers or attendants thereon are liable to drive too close to the elevator. 95

The link-belt N, herein employed for operating the belt-driving roll at the delivery end of the elevator, passes over the sprocket 120 and extends back to the body of the machine, where it passes around and is operated by a belt-driving sprocket, thereby providing between the two sprockets a flexible power-transmitting connection, which permits the elevator to be readily raised and lowered from its delivery end. 100

Where a removal of one or more of the sections of the extension portion of the elevator is contemplated, the belt will be made in sections proportioned in length to contemplated change in length of the elevator, so that by removing one or more sections of the belt it 110 can be adjusted in length to the change in length of the elevator. As a simple and desirable construction of connection between the meeting ends of the lengths or sections of belting, a stout flexible strip, 121, Fig. 10, is along 115 a portion of its width secured to one of the meeting edge portions of the belt by rivets 122 and along the opposite portion of its width detachably secured to the other one of the meeting edge portions of the belt by short 120 bolts 123, provided with nuts that can be tightened up in order to clamp this transverse connecting strip and belting together. At the ends of this strip are short flexible pieces 124, arranged transversely to the length of strip 121 and alongside of and parallel with the longitudinal edges of the belting. These end pieces, 124, can be separate from or integral 125 with the cross-strip 121, and are, like the cross-

strip, secured to one end portion of the belt by rivets and detachably secured by short bolts and nuts to the opposing end of the belting. This arrangement permits the disconnection of the belt-sections by unscrewing the nuts and removing the bolts, and is of particular value in an elevator for the purposes of a machine of this character, it being observed that the pieces 124 prevent wear and tear along the longitudinal side edges of the belt at the joint, and that with the comparatively narrow strip 121, secured across the belt, and the comparatively narrow strips 124, parallel with the length of the belt, a strong and at the same time sufficiently flexible joint is provided.

To prevent the lower leaf of the elevator belt from sagging to an undesirable extent, the elevator is provided at one or more points along its length with one or more idler belt-rolls, 125, over which the lower leaf of the belt may pass. These rolls 125 are conveniently journaled in bearings secured to the under sides of the longitudinally-arranged side bars, 79, of the main frame, so as to place the rolls in proper position for upholding the lower leaf of the belt, one of such belt supporting rolls being in Fig. 8 mounted in bearings at the under side of the portion of the elevator that extends under the main body or platform frame A of the machine, while in Fig. 31 a like roll is shown similarly applied to the extension portion of the elevator.

In addition to the set of belt-rolls 80, arranged in a plane proper for supporting the upper leaf of the elevator-belt, the elevator is provided with a second set of idler belt-rolls, 126, Figs. 8 and 31, arranged in a plane below the plane of the rolls 80 and mounted with relation to the cross bars or braces of the elevator-frame to prevent the lower leaf of the belt from coming in contact therewith, it being seen that the belt passes under those guard-rolls 126, as in Fig. 8.

To insure the requisite rigidity of the extension portion of the elevator, particularly where such extension comprises several connected frame-sections, longitudinally-arranged side truss-rods, 127, can be employed, as in Fig. 11, wherein the application of one of such rods is illustrated. In said figure the truss-rod 127 is somewhat bowed or bent down intermediate of its ends and at its ends adjustably attached to brackets or bearings 128, one of which is secured to a side of the elevator frame section that is next adjacent to the frame-section which extends under the main body-frame of the machine, while the remaining one of the bearings 128 is, as indicated in dotted lines, attached to a side of the elevator frame-section that is at the delivery end of the elevator.

To the elevator frame-section that is understood to be intermediate of the said two sections carrying bearings for the ends of the rod a cleat, 129, is applied and arranged to bear downward against the rod, which, when tightened up by any ordinary mechanical means—

such as by nuts on its threaded terminals—will engage and bear upwardly against the lower bearing-surfaces of the cleats 129. The rear supporting-wheels, 130, of the machine are loosely mounted upon a rotary axle, P, Fig. 20, and prevented from running off from the ends of such axle in any suitable way—for example, by collars 131, bolted to the ends of the axle 75 and received within suitable recesses, 132, in the outer ends of the hubs—means being provided whereby during the advancement of the machine connection may be established between the rear wheels and rear axle, as hereinafter particularly set forth.

The rear axle, P, has at two or more points bearings in boxes Q and Q', that are clipped to the lower bar, 133, of the rear bolster, R, herein provided for supporting the rear end 85 of the main body or platform frame of the machine, which frame may, for example, have its longitudinal sills secured upon the upper bar, 134, Fig. 14, of the rear bolster. These boxes may have a like construction, with the exception that the box Q' is provided with a bearing, 135, Figs. 23 and 24, for the rear end 90 of a rotary shaft that carries a clutch, as hereinafter described. With regard to certain features of construction involved in all of these 95 boxes, each box is provided with suitable bearings for the rotary axle and with one or more (but preferably with a couple of) recesses, 136, formed in their lower interior axle-bearing-surfaces, and providing receptacles into which 100 lubricating matter—such as cotton or other waste and some suitable lubricant—can be introduced through passages 137, which are formed to extend downwardly through a side portion of the box, as illustrated in Fig. 24, 105 wherein one of such passages is arranged to form the entrance to a lubricant-receptacle, 136. In this way a quantity of lubricating matter sufficient to last a long time can be introduced into boxes, thereby permitting the 110 easy running of the axle. The boxes are divided or made in halves to permit them to be readily and properly cast, it being obvious that the parts of each box can be securely bolted together and the box firmly attached 115 to the wooden or other bar 133 by clips 138.

As a means for connecting one of the rear wheels with the rotary axle P during the advancement of the machine, so as to permit the elevator-belt to be driven from such axle by 120 means hereinabove described, and to automatically disconnect said wheel from the axle in backing the machine, the rotary axle is at a point along its length provided with a hub, 139, Figs. 20 and 21, which is keyed upon the 125 axle and provided with ratchet-teeth that are to be engaged by a pawl on the hub of the supporting-wheel when the machine is drawn forward, said pawl, however, being arranged to ride over the ratchet-teeth in backing the 130 machine. The hub 139 herein shown is provided at one end with an annular chamber, 140, containing an annular line of ratchet-teeth, 141, and the hub 142 of the rear sup-

porting-wheel next adjacent to the internally-toothed hub 139 is at its inner end provided with a cap, 143, secured to the hub and carrying one or more (but preferably a couple of) 5 spring controlled pivoted pawls, 144, which during the advancement of the machine engage in the line of ratchet-teeth 141, but ride over such teeth in backing.

The hub 145 of the rear supporting-wheel, opposite the rear supporting-wheel hereinbefore last referred to, like its companion wheel-hub 142, carries one or more pawls arranged to engage a ratchet on the rotary axle during the advancement of the machine, but to ride along 10 the ratchet-teeth in backing. The ratchet for the pawl or pawls carried by the rear-wheel hub 145 is, however, formed with or rigid upon a bevel-gear, 146, which can have its central portion adapted to provide a hub, 147, 15 which, like the ratchet plate or hub 139, is herein provided with an internally-arranged set of ratchet-teeth for one or more pawls understood to be pivoted to a cap, 148, that is fitted to the wheel-hub 145 and equipped 20 with one or more of such pawls similar to the cap 143, that is fitted to the rear-wheel hub 142. The said gear 146, having a hub, 147, provided with an internally-arranged set of ratchet-teeth, is shown in Fig. 4, wherein the 25 nearest rear supporting-wheel is understood to be removed for convenience of illustration. The bevel-gear 146 is rigid upon the rotary axle P, and is employed for operating a rotary shaft that forms an element in the power-transmitting connection between the elevator driving-belt N and the gear 146.

By the foregoing arrangement of rotary axle extending through the boxes and provided with a driving-gear and the means set forth 40 for establishing a rigid connection between the wheels and the axle during the advancement of the machine, but permitting the wheels to run loose upon the axle in backing, provision is made for the application of a comparatively 45 large quantity of lubricated cotton or other waste at the points where the axle turns in its bearings, it being observed that the impracticability of supplying the hubs of the rear wheels with such lubricating matter will be 50 obvious. In this way, therefore, the axle-bearings can be kept lubricated for a long time, and at the same time a simple arrangement provided for driving the link-belt N from the 55 machine, will be in rigid connection with the axle, which in turn directly causes the rotation of gear 146.

The box Q' for the rear axle is provided with the hereinbefore-mentioned bearing 135, 60 having a passage for the introduction of any suitable lubricating matter, which said bearing provides a support for the rear end of a short rotary power-transmitting shaft, 149. (Shown in Figs. 1, 4, 14, and 15, but best represented in Figs. 14 and 15, wherein the clutch R, for connecting and disconnecting the driving-power with and from the link-belt N, is

particularly illustrated.) The rotary shaft 149 is driven from the gear 146 when the latter is operated, to which end a small bevel-gear, 70 150, arranged to engage the gear 146, is secured upon the shaft 149.

The clutch gland or member 151 is keyed upon shaft 149, so as to rotate with but slide along the same, and an opposing gland or 75 member, 152, is loosely fitted upon the shaft. The clutch-gland 152 is adapted to provide a sprocket for the link-belt N, by which the belt-roll at the delivery end of the elevator is driven, and is further provided at one end with teeth 80 or lugs 153, Fig. 16, that are to be engaged by similar teeth or lugs, 154, Fig. 17, on the shifting clutch-gland 151 when the latter is shifted in position to throw it in clutch with the gland 152. The shifting clutch-gland 151 is made 85 substantially bell-shaped, and the opposing gland 152 is provided with an annular flange, 155, which provides a recess or chamber within which a portion of the flared end of the shifting clutch-gland is received when the two 90 glands are in clutch. When, therefore, the two glands are in clutch, the flange 155 covers the end of the flared portion of gland 151, within which latter the teeth 154 are located, and hence all dirt falling upon the clutch will 95 be shed off and effectively prevented from getting into and clogging up the clutch.

The shifting gland 151 carries and is free to rotate within a sleeve, 156, which is held against rotation by an inclined bar, 157. This 100 bar, which is at one end pivotally attached to the sleeve 156 and at its opposite end attached to the main body-frame of the machine, (for example, to the middle longitudinal sill, 3,) is capable of sufficient movement to permit the 105 desired extent of end motion on the part of the shifting clutch-gland.

The hand-lever 158, Fig. 4, for example, rises from the rear attendant's platform on the main body-frame of the machine, so as to be within 110 convenient reach of an attendant standing thereon, and is at its lower end connected by the connecting rod 159 with one end of a link or lever, 160. The link or lever 160, which is at its forward end pivotally connected with the 115 operating-rod 159, is at its rear end pivotally attached to a bearing-piece, 161, that is secured to the lower bar, 133, of the rear bolster. This link or lever 160 is also connected with the bar 157 by a link or lever, 162, which is at one 120 end pivotally attached to the bar 157 at a point near the shifting clutch-gland and at its opposite end pivotally attached to the link or lever 160 at a point intermediate of the ends of the latter. The operation of these links or levers 125 is illustrated in Fig. 15, wherein their relative position when the clutch is closed is shown in full lines and their relative position when the clutch is open indicated in dotted lines. By such arrangement the links or levers 160 and 162 co-operate to provide a compound 130 lever or toggle which when the clutch members are closed together locks them in clutch, since in such case the links or levers 160 and 162

are in line, substantially as shown. The clutch as a whole possesses great strength, and, together with its operating devices, provides a clutch mechanism particularly adapted to a machine of the present kind.

As hereinbefore mentioned, the rotary shaft 149 is at its rear end journaled in a bearing provided by one of the boxes for the rear axle. The forward end of this rotary shaft is mounted 10 in a box, 163, adapted to receive a suitable quantity of lubricating matter, and herein secured to the inclined brace-bar 100, which, it will be remembered, in addition to being secured to the lower end of a standard, 102, of 15 the elevated frame L as a lateral brace for such standard, also provides a bearing for a pivot by which a bracket-plate, 98, Fig. 14, attached to one corner of the hinged elevator-frame extension, is supported, thereby providing a compact economical arrangement of parts, which, 20 while affording the greatest required strength, tends to greatly simplify the general construction.

The front supporting wheels, 164, of the machine are secured to the forwardly-arranged rotary axle S, which at desired points between the wheels passes through boxes T. These boxes are secured by clips or other suitable fastenings to a bar, 165, that is arranged over 30 and parallel with the axle and adapted to support the front bolster, U. The boxes T are adapted to provide receptacles for lubricating matter, whereby a lubricant can be applied at the points where the axle turns in the bearings 35 afforded by such boxes. The formation of the lubricant receptacles in these boxes can be similar to the formation of lubricant-receptacles in the boxes for the rear axle, it being observed that in Fig. 36 the boxes T are provided with receptacles 166, containing lubricant cotton or other waste, which can be introduced through passages 137, formed in lateral enlargements 168 of the boxes, as indicated in Figs. 14 and 37, wherein such passages are understood to substantially correspond with the construction of passage 137. (Shown in Fig. 24.)

The front bolster, U, is pivoted by a king-bolt, 169, upon the bar 165, to which the boxes 50 T are clipped, the arrangement of bearings for such bolt being particularly illustrated in Figs. 37, 38, and 39. The front bolster is also provided with a half-circle, V, which is firmly secured by clips or bolts to the lower bar, 170, 55 of the frame that constitutes the bolster, as best indicated in Fig. 36. The bar 165, which may be termed the "axle-bar," is provided upon its upper side with suitable bearings, 171, Fig. 36, for the half-circle V, which latter 60 is desirably made of wood and provided along its under side with a metal wearing-surface formed by a metal strap, 172, secured to the under side of the wooden half-circle and bent reversely at its ends, so as to permit the 65 securing of its terminals to the upper side of the wooden half-circle, as indicated in Fig. 37.

The lower bar, 170, of the front bolster is at

its middle embraced by a bent plate or clip, 173, Fig. 39, which is bolted to said bar, and at its ends, which extend laterally to the rear 70 from the bolster bar, provided with bolt-holes for the king-bolt 169.

A bent plate or clip, 174, is bolted to the middle of the axle bar 165, but formed to drop somewhat below such bar, so as to provide 75 room for the rotary axle, which at this point passes between the bar 165 and the lower horizontal end portion of the clip. The upper and lower horizontal end portions of clip 174 extend back from the axle-bar and axle and are 80 provided with bolt-holes for the king-bolt, by which the two clips 173 and 174, that are respectively secured to the bolster and the axle-bar, are pivoted together. The lower clip, 174, provides a bearing for the upper clip and has 85 its horizontal end portions braced by angle-plates 175, which are fitted between and bolted to said end portions of the clip 174. These angle-plates are also bolted to the rear side of the axle bar 165, to which end they can be secured 90 to the axle-bar by the horizontally-arranged bolts employed for attaining a secure connection between the axle-bar and the clip. In this way the clip 174 and the angle-plates 175 are respectively clamped against opposite sides of 95 the axle-bar by the bolts, for which latter they afford suitable bearings. Said clip and one of the angle-plates may also afford bearings for an eyebolt, 176, to which the forward end of the draft-chain H can be attached, in which 100 ease the eyebolt desirably extends through the axle-bar 165 as well as through one of the angle-plates and the vertical portion of clip 174, such arrangement affording an exceedingly 105 substantial bearing for the bolt and permitting its securement at a point which will place its connection with the draft-chain H back of and substantially in line with the pole 177, Fig. 14, of the machine.

The king-bolt extends both above the clip 110 173 and below the clip 174. The end of the king-bolt which is thus extended above the upper clip has a bearing in the forward end of a bent bar, W, while its end which is extended below the lower clip has a bearing in the forward end of an inclined bar, 178. The bar W is bent at a point between its ends, and at its bend is divided, so as to embrace a portion of the middle longitudinal sill, 3, of the main body or platform frame, the division of the bar W 115 at such point being shown at 179, Fig. 14. The two sides of this divided portion of the bar W are firmly bolted to the sill 3, thereby rigidly holding the bent bar in place. The bar W is 120 by such arrangement formed with a pair of legs extending downwardly from its point of securement to the body-frame, the front leg, 180, being extended forwardly and inclined downwardly to a point proper to provide a bearing for the upper end of the king-bolt, 125 while the rear leg, 181, which drops down from the sill, is at its lower end bolted to the rear portion of the half-circle V, so as to establish a rigid connection between such por-

tion of the half-circle and a middle portion of the main body or platform frame of the machine.

As a further means for bracing and steady-
5 ing the half-circle, short inclined brace-rod-
182, arranged diagonally to the length of the
machine, are at their upper ends secured to the
middle longitudinal sill, 3, and at their lower
10 ends secured to the half-circle at points for-
ward of the connection between the half-circle
and the bar W, although the bar W is gener-
ally sufficient as a stay and support for the
15 rear or middle portion of the half-circle with-
out the auxiliary brace-rod, which, however,
may be employed in machines of the largest
grade.

The inclined bar 178 is at its rear upper end
suitably secured to the main body or platform
frame of the machine and at its lower end
20 provided with an eye or bearing for the lower
end portion of the king-bolt, which, however,
may, if desired, be extended below such bear-
ing to an extent to provide between the same
and the head on its lower end room for an eye
25 on the forward end of a stay-rod or stay-chain,
183, arranged to extend from king-bolt back
to the elevator, as in Fig. 14, it being observed,
however, that this stay-chain could at its for-
ward end be attached to any other suitable
30 device carried by the axle-bar or by the front
bolster.

As hereinbefore mentioned, the work that
is to be performed by these machines demands
great strength of construction, and for heavy
35 work it is necessary to make the machines of
considerable size. It is therefore a matter of
much importance that while involving all
requisite strength the machine should be made
as light as possible, and that with a view to
40 decreasing the weight the simplest and most
economical disposition of parts compatible
with the necessary rigidity and strength to
withstand the great draft and wear and tear
should be observed.

45 As a brief summary of several features of
construction hereinbefore set forth in detail
and serving to attain these last-mentioned ends,
it may be observed, in conclusion, that the ele-
vated frame L, while serving to support the
50 winding drums or shafts for the chains by
which the receiving and delivery ends of the
elevator can be raised and lowered, also pro-
vides at the lower ends of its uprights 101 and
102 supports for bearings allotted to the pivots
55 at the hinged end of the elevator-extension.
These uprights therefore require rigid connec-
tion with the main body-frame of the machine,
both for the purposes of the upper portion of
frame L as a whole and for their service as
60 supports for said pivot-bearings. To such end
one of these uprights is braced in one direction
by a rod, which affords a bearing for the end of
bar G, and in an opposite direction braced by
a short brace, 60, which, in conjunction with
65 said rod, constitutes a double brace, said up-
right being further braced by a bar, which in
turn affords a pivot-bearing for one of the piv-

ots at the hinged end of the elevator-extension.
The remaining upright of frame L is braced by
a bar which, while providing a pivot-bearing 70
for one of the pivots at the hinged end of the
elevator-extension, also supports a journal-box
for one end of the power-transmitting shaft 149.

The front and rear axle-bars, 133 and 165,
can be made of wood, and also the construc- 75
tion and mode of securement of the half-circle
V permit it to be made of wood, and at the
same time to involve all desired rigidity and
strength.

What I claim as my invention is— 80

1. In a grader and ditching-machine, the
combination, substantially as hereinbefore set
forth, with the plow-beam carrying a plow, of
the swinging controlling-bar pivotally sup- 85
ported at one end upon a fixture at one side of
the body-frame of the machine and at its oppo-
site end flexibly connected with the plow-beam
in advance of the plow and an adjustable flexi-
ble draft attachment, H, applied to the swing- 90
ing controlling-bar at a point between the end
of the controlling-bar that is connected with
the plow-beam and the pivotally-supported
end of said controlling-bar, for the purpose
described.

2. In a grader and ditching-machine, the 95
combination, substantially as hereinbefore set
forth, with the plow-beam carrying a plow, of
the swinging controlling-bar constituting the
draft-bar from which the plow is drawn and
flexibly connected with the plow-beam at a 100
point in advance of the plow and at one side of
the plow-beam, so as to place such connection
substantially in a line directly ahead of the
mold-board of the plow, for the purpose de-
scribed. 105

3. In a grader and ditching-machine, the
combination, substantially as hereinbefore set
forth, with the suspended plow-beam carrying a
plow at its rear end portion and at its forward
end portion carrying a caster-wheel, of the 110
draft and controlling bar G, flexibly connected
with the plow-beam in advance of the plow,
but in rear of the caster-wheel, and the draft-
chain attached to said draft and controlling
bar, for the purposes described. 115

4. In a grader and ditching-machine, the
combination, with the suspended plow-beam
carrying a plow, of the draft and controlling
bar G, flexibly attached to the plow-beam in
advance of the plow, and a draft-connection, 120
such as set forth, attached at its rear end to
said draft and controlling bar and at its for-
ward end attached to a fixture of the ma-
chine at a point substantially between the two
sides of the body-frame, whereby the draft is 125
substantially coincident with a line along the
longitudinal center of the body frame, for the
purpose described.

5. In a grader and dumper, the combination,
substantially as hereinbefore set forth, with the 130
plow-beam carrying a plow, of the rear con-
trolling-bar, E, capable of a swinging move-
ment toward the front and rear of the machine
and flexibly connected with the plow-beam in

- rear of the plow, and the forward controlling-bar, G, flexibly connected with the plow-beam in advance of the plow and pivotally supported to swing toward the front and rear of the machine in correspondence with said swing on the part of the rear controlling bar, whereby both bars can swing in unison in adjusting the working position of the plow to either the front or rear, for the purpose described.
- 10 6. In a grader and ditcher, the combination, substantially as hereinbefore set forth, with the plow-beam carrying a plow and an elevator to which the delivery is made from the plow, of the rear swinging controlling-bar flexibly connected with the plow-beam in rear of the plow by an adjustable hinge-connection adapted for adjustment to permit the tilt of the plow, and the forward controlling-bar flexibly connected with the plow-beam in advance of the plow and adjustable endwise upon its pivotal support, whereby the plow, when tilted, may be brought into proper working position relatively to the receiving end of the elevator, for the purpose described.
- 15 7. In a grader and ditcher, the combination, with the plow-beam carrying a plow, of the horizontally-swinging controlling-bars respectively attached to the plow-beam in advance and to the rear of the plow and both capable of end adjustment, for the purpose set forth.
- 20 8. In a grader and ditcher, the combination, with the plow-beam carrying a plow, of the bar G, flexibly attached to the plow-beam in advance of the plow and having both an end and lateral adjustment, substantially as set forth, the said end adjustment being in a direction transversely to the length of the plow-beam, and the lateral adjustment being in a direction substantially coincident with the line of progression, for the purpose set forth.
- 25 9. In a grader and ditcher, the combination, with the plow-beam carrying a plow, of the bar G, flexibly attached to the plow-beam in advance of the plow and having both a horizontal and vertical swing, and the draft chain attached to said bar, for the purpose described.
- 30 10. In a grader and ditching-machine, the combination, substantially as hereinbefore set forth, with the plow beam carrying a plow, of the horizontally and vertically swinging bar G, flexibly attached to the plow-beam in advance of the plow and having an end adjustment transverse to the line of progression and a lateral adjustment in a direction substantially coincident with said line of progression, for the purpose described.
- 35 11. In a grader and ditching-machine, the combination, with the plow-beam carrying a plow, of the forwardly-arranged swinging controlling-bar flexibly connected with the plow-beam in advance of the plow by a pivot, 49, supported from and at one side of the beam and connected with the swinging controlling-bar by a compound joint, for the purpose described.
- 40 12. In a grader and ditching-machine, the

combination, substantially as hereinbefore set forth, with the plow-beam carrying a plow and provided at one side with a pivot, 49, arranged in advance of the plow, of the swinging bar G, having at one end a bearing for said pivot, for the purpose set forth.

13. In a grader and ditching-machine, the combination, substantially as hereinbefore set forth, with the plow-beam carrying a plow and provided at one side with a pivot, 49, arranged in advance of the plow, of the swinging bar G, provided at one end with a recess, 50, and with a pivot-bearing, 51, arranged at one side of said recess and affording a bearing for the pivot 49, which extends through the said recess in the end of the bar, for the purpose set forth.

14. In a grader and ditching-machine, the combination, substantially as hereinbefore set forth, with the bar G, flexibly attached at one end to the plow-beam, of the bearing 44, supporting the opposite end of said bar, and the pivot whereby the bar is pivotally attached to said bearing, for the purpose set forth.

15. In a grader and ditching-machine, the combination, substantially as hereinbefore set forth, with the bar G, flexibly attached at one end to the plow-beam, of the support 44 for the opposite end of said beam, formed at one end of a brace-rod, 59, for the purpose described.

16. In a grader and ditcher, the combination, substantially as hereinbefore set forth, with the swinging plow-beam controlling-bar G, of its pivotal support 44, secured to the lower portion of the upright of an elevated frame, L, and having a rod, 59, that is secured to the main body-frame of the machine, for the purpose described.

17. In a grader and ditcher, the combination, substantially as set forth, with the plow-beam carrying a plow, of the controlling-bar flexibly connected at one end with the plow-beam and at its opposite end pivotally attached to a bearing which in turn has a sliding pivotal connection with a guide-support, for the purpose described.

18. In a grader and ditcher, the combination, substantially as hereinbefore set forth, with the swinging bar E, flexibly connected with the plow-beam, of the bearing 29, having a pivot arranged to slide in a guideway extending transversely to the line of progression, the bar E being pivotally attached to said bearing, for the purpose set forth.

19. In a grader and ditching-machine, the combination, substantially as hereinbefore set forth, with the bar 33, provided with a guideway, 32, of the swinging bar E, pivotally attached to a bearing having a pivot arranged to both turn and slide in the guideway of said bar 33, for the purpose described.

20. In a grader and ditching-machine, the combination, substantially as set forth, with the bar 33, provided with a guideway, 32, and applied as a brace between the pendent bar 34 and a longitudinal sill of the main body-frame

of the machine, of the swinging bar E, connected with a pivot which is arranged to turn in and slide along the guideway 33, for the purpose described.

5 21. In a grading and ditching machine, the combination, with the plow-beam carrying a plow and suspended by cords or chains attached to its forward and rear end portions, whereby the plow-beam shall hang substantially as set forth, of the foot presser-bar 61, secured to and rising from the plow-beam and provided with a foot-rest which is within convenient reach of the foot of an attendant standing upon the machine, said presser-bar being free to move in unison with the longitudinal movements and side tilt of the beam, substantially as and for the purpose described.

22. In a grader and ditching-machine, the combination, substantially as hereinbefore described, with the plow-beam carrying a plow, of the caster-wheel I and a scraper, 70, arranged over the caster-wheel, for the purpose described.

23. In a grader and ditching-machine, the combination, with the plow-beam carrying a plow, of the caster-wheel I, the swiveled hub 66, carrying bearings for the caster-wheel journals and provided with a scraper-support carrying a scraper, 70, which projects beyond its support, said support having its under side formed to curve in a direction away from the periphery of the caster-wheel, substantially as herein described, and for the purpose set forth.

24. In a grader and ditching-machine, the combination, with the plow-beam carrying a plow, of the caster-wheel I, the caster-wheel standard attached to the plow-beam and provided with a rotary hub, 66, carrying arms 71, which are in turn provided with boxes for the journals of the caster-wheel, substantially as described, and for the purpose set forth.

25. In a grader and ditching-machine, the combination, with the plow-beam and a side-delivery plow arranged for delivering the plowed-up earth onto an elevator, of the plow-standard 8, pivoted to the plow-beam, and the bar 10, attached at its lower forward end to the plow and at its upper rear end adjustably pivoted to a bearing secured to the plow-beam, substantially as described, and for the purpose specified.

26. In a grader and ditching-machine, the combination, substantially as set forth, with the plow having a side delivery, of an elevator provided with an endless conveyer-belt and guides forming along the conveyer-belt a guideway for the matters delivered from the plow, and a guard arranged opposite the plow at the forward corner of the elevator for directing stalks onto the conveyer-belt.

27. In a grader and ditching-machine, the combination, with the plow having a side delivery, of the elevator provided with an endless conveying-belt and the guideway side portions, 104, and the guard K, extending from one of said guideway side portions at the re-

ceiving end of the elevator, substantially as described, and for the purpose specified.

28. In a grader and ditching-machine, the combination, with the plow having a side delivery, of the elevator provided with an endless conveyer-belt and the guideway side portions, 104, one of said guideway side portions being at the receiving end of the elevator provided with an extension, 76, substantially as and for the purpose set forth.

29. In a grader and ditching-machine, the elevator arranged to receive matters delivered from the plow, and comprising in its structure a frame having sloping sides 81, combined with an endless conveyer-belt having the edges of its upper leaf extended to substantially meet the upper longitudinal edge portions of said sloping sides, substantially as and for the purpose set forth.

30. In a grader and ditching-machine, the combination, substantially as hereinbefore set forth, with the plow, of the elevator comprising the endless conveyer-belt, the guides F', arranged over and along the upper leaf of the conveyer-belt, and the sides 81 of the elevator-frame sloping from the edge portions of such upper leaf of the conveyer-belt, for the purpose described.

31. In a grader and ditching-machine, the combination, substantially as hereinbefore set forth, with the plow having a side delivery, of the receiving-end frame-section of the elevator suspended to bring it in position to receive from the plow, the extension frame-section of the elevator supported by a hinge-joint from the main body-frame of the machine, the endless conveyer-belt, both of said elevator-sections, and the guides 104 and 105, arranged substantially as set forth and meeting substantially over the joint between the two elevator frame-sections, for the purpose described.

32. In a grader and ditching-machine, the elevator arranged to convey the plowed-up soil from the plow to the point of delivery, and comprising in its structure an endless conveyer-belt and a sectional frame with the guide-sections 105 and 106, arranged to form the sides of a guideway extending over and along the upper leaf of the conveyer-belt and provided at their meeting ends with locking devices such as set forth, for the purpose described.

33. In a grader and ditching-machine, the elevator adapted for conveying plowed-up soil from the plow to the front of delivery, and comprising in its structure the extension portion which extends laterally from the body portion of the machine as an extension of the elevator-section below the body-frame, and which is composed of two or more frames detachably connected together by separable hinge-joints, whereof one member upon one frame is detachable from the other member upon the next succeeding frame, substantially as described.

34. In a grader and ditching-machine, the combination, with the elevator adapted and

arranged for conveying plowed-up soil from the plow to the point of delivery and the link-belt N, passing over a sprocket that is connected with the conveyer-belt driving-rod 5 at the delivery end of the elevator, of the shield M, arranged to cover said sprocket, substantially as and for the purpose described.

35. In a grader and ditching-machine, the combination, substantially as hereinbefore set forth, with the endless soil-conveying belt of the elevator, of the rotary rear axle extending through boxes that are connected with the main frame of the machine, the rear wheels arranged loosely upon said axle, a driving-gear 15 fixed upon the axle, a pawl-and-ratchet device for establishing a rigid connection between one of the wheels and said driving-gear during the advancement of the machine, a power-transmitting connection between the driving-gear, and a belt-roll by which the endless conveyer-belt is driven, for the purpose described.

36. In a grader and ditcher, the combination, with the soil-conveyer belt of the elevator, the rear wheels and axle, and the driving 25 chain or belt N, of the clutch R, arranged in a power-transmitting mechanism for operating the driving chain or belt N from the rear wheels, and comprising the sprocket-gland 152, having a flange, 153, and the flared shifting 30 clutch-gland 151, adapted to engage the sprocket-gland, substantially as and for the purpose described.

37. In a grader and ditcher, the combination, with the soil-conveying belt of the elevator, of a clutch interposed in a power-transmitting connection between the endless conveyer-belt and one of the rear main supporting-wheels, and a clutch-shifting device comprising the two pivotally-connected links or 40 levers 160 and 162, one of which is connected with the shifting clutch-gland and the other connected with an operating-lever, substantially as described.

38. In a grader and ditching-machine, the combination, with the main body-frame and an upright, 102, for the purpose set forth, of the brace-bar 100, attached to the main frame and to said upright, and carrying the box 163 for a rotary power-transmitting shaft, 149, substantially as and for the purpose described.

39. In a grader and ditching-machine, the

combination, substantially as hereinbefore set forth, with the main body-frame, of the half-circle V, secured to the front bolster, and the bent bar 181, attached at its bend to the main body-frame, and having one end secured to the half-circle and its remaining end provided with a bearing for the king-bolt, for the purpose described. 55

40. In a grader and ditching-machine, the combination, with the main body-frame, of the front bolster, U, the axle bar 165, the clips 170 and 174, respectively secured to the bolster and the axle-bar, the king-bolt 169, and the braces W and 178, both secured to the main body-frame and respectively providing bearings for the upper and lower ends of the king-bolt, for the purpose described.

41. In a grader and ditching-machine, the combination, with the front axle-bar, 165, of 70 the swinging bar G and the draft-chain connecting said swinging bar with the axle-bar, for the purpose set forth.

42. In a grader and ditching-machine, the combination, with the front axle-bar, 165, of 75 the clip 174, secured thereto, a plate, 175, secured to the front axle-bar and extending between the ends of the clip, and the draft-chain H, attached to a bolt passing through the plate 175 and the clip 174, for the purpose set forth.

43. In a grader and ditching-machine, the combination, with a sectional elevator, of a sectional belt having a joint consisting of the transverse strip 121, permanently secured to 85 one of the meeting ends of the belt and detachably secured to the other one of said meeting ends of the belt, and the longitudinally-arranged strips 124, similarly secured to the belt, substantially as described.

44. The combination, with the plow-beam, of the bar E, the plate 39, secured to bar E and pivotally connected with the plow-beam, and the bar 40, connected with the plow-beam and said bar by a pivotal joint at one end and 95 a sliding pivotal connection at its opposite end, substantially as described.
